UNITED STATES PATENT OFFICE.

WILLIAM SEIDEL, OF CHICAGO, ILLINOIS, ASSIGNOR TO AMERICAN PATTERN & MODEL CO., OF CHICAGO, ILLINOIS, A CORPORATION OF ILLINOIS.

MOLDER'S FLASK.

1,108,630.

Specification of Letters Patent. Patented Aug. 25, 1914.

Application filed April 9, 1914. Serial No. 830,648.

To all whom it may concern:

Be it known that I, WILLIAM SEIDEL, a citizen of the United States, residing at Chicago, in the county of Cook and State of Illinois, have invented certain new and useful Improvements in Molders' Flasks, of which the following is a specification.

The present invention relates to a combined molder's flask and match board used 10 in casting operations.

The objects of the present invention are to provide means for centering the cope section and drag section of the flask with respect to the match board, and to provide 15 centering means which will enable an independent centering of either the cope or drag section with respect to the match board as well as a centering of both of said sections with respect to the board.

20 A further object of the invention is to provide means for giving a uniform and even initial lifting movement to the cope and drag sections when it is desired to remove the same from the match board.

25 A further object of the invention is to attach metal strips to the match board in a manner to prevent a warping or breaking of the same.

30 A further object of the invention is to provide a metallic member along the outer edges of the match board which is configured to permit a dovetailing of the edges of the match board with said strip, thus reinforcing the said edges.

35 The invention further consists in the features of construction and combinations of parts hereinafter described and claimed.

In the drawings: Figure 1 is an end elevation of the flask of the present invention; 40 Fig. 2 is an enlarged plan view of one end of the said flask; Fig. 3 is a vertical section through one end of the flask; Fig. 4 is a section on line 4—4 of Fig. 6 showing the centering members carried by the cope section and the centering members carried by the drag section; Fig. 5 is a section on line 5—5 of Fig. 6 showing the centering member for the drag section only, and showing how the drag section may be centered independently 45 of the cope section; Fig. 6 is an enlarged vertical sectional detail of one end of the flask; and Fig. 7 is a plan view of the entire flask with the initial lifting members and the centering members removed.

In the operation of molding where a two piece pattern is used, one piece of the pattern can be secured upon one side of the match board and the other piece upon the opposite side and alined therewith. The cope sections and drag sections are then inserted in position above and below the match board respectively and are filled with sand and tamped. The cope and drag sections are then removed with the impressions of the patterns upon adjoining faces thereof and are combined to form the completed mold. The present invention deals more particularly with the means for centering the said cope and drag sections with respect to the match board and with the means for giving to the cope and drag sections an initial separating movement from the match board.

Referring now to the drawings, and particularly to Fig. 1, the device as there shown, consists of the upper or cope section 8, the lower or drag section 9, and the match board 10 placed between such sections. The cope and drag section each are as shown of rectangular form and are each formed of two sections 10^a and 10^b hinged as at 11 in Fig. 7 and the sections are locked together by a suitable locking member 12, as in Fig. 7. The form of the locking member will be clearly understood from Figs. 1 and 2 and consists of a body formed with a U-shaped recess 13 which embraces abutting edges of the sections of the frame. The locking member is pivoted as at 14 and is formed with a suitable finger piece 15. The manner in which this locking member performs its work is obvious from the drawing. As stated, in casting operations, where split patterns are employed one section of the pattern is fixed to one side of the match board and the other section to the other side and the two sections are placed in alinement. It is obvious that to successfully aline and match the impression in the sand of the cope and drag sections it will be necessary to properly aline the cope and drag sections with respect to each other and with respect to the match board. This is accomplished in the present invention by a simple and effective construction. This centering means, as illustrated, comprises vertically extending posts 16 which are formed integrally or fixedly secured to the plate-like

members 17, (see Fig. 4). There are two of the members and posts employed which are arranged upon opposite sides of the match board and in alignment with one another. 5 Each plate-like member extends inwardly beyond the end of the match board and is cut away as at 18 so that the match board dovetails therewith. Each post 16 is, as shown in the drawings, of triangular formation in cross section and extends above and 10 below the board. The cope section has secured thereto plates 19 arranged upon opposite sides of the section and in alignment with one another. Depending from each 15 plate is a V shaped end 20 arranged and adapted to embrace the posts 16 as will be seen from Fig. 4. Plates 21 are attached to the drag section which plates are arranged upon opposite sides of said section and in 20 alignment with one another. These plates are of triangular formation in cross sections as will be seen from Figs. 4 and 5 and these plates have a portion thereof configured to provide inwardly extending ends or fingers 25 22, which engage the surface of the posts 16 beyond the points of engagement of the end 20 with said post. This will be clearly understood from Fig. 4. It may be said that the end 20 telescopes with respect to the 30 plate 21. By this arrangement means are provided for centering the cope and drag section with respect to the match board which means are arranged to act independently of one another whereby the centering 35 of the drag section is brought about independently of the centering of the cope section and when the two sections are in position both are centered with respect to the match board. It is obvious that the end 20 40 affords a means for centering the cope section which is in no wise dependent upon the positioning of the drag section, and that the means for centering the drag section are such as to be in no wise dependent upon the 45 positioning of the means for centering the cope section. Thus in case it is desired to use either section without the other a centering means is provided.

As stated, another object of the invention 50 is to give to the cope and drag sections an initial lifting movement away from the match board which will lift them evenly and without any disorganization of the sand. Such means in the construction shown, 55 consists of handle members 23 on the cope section, and handle members 24 on the drag section. The handle members on each section are arranged upon opposite sides of the section with which they are associated, and are 60 oppositely disposed with respect to one another. The handles are pivoted at each end to ears 25 which ears are secured to or formed integral with the said sections, and each handle at each side thereof has a portion 65 26 extending beyond the pivotal connec-

tion and this extending portion of the handle constitutes in effect a lever. When the handles are moved, as shown by dotted lines in Fig. 3, the ends 26 press against the match board and lift or elevate the section away 70 from the match board in an obvious manner. After the initial lifting movement a complete removal of the sections from the match board can be easily effected. The acting ends 26 bear against metal strips 27 which 75 provide a firm surface for the ends to act against and also serve as a binding for the edge of the match board to prevent a warping and distortion of the same. These strips overlie the point of juncture of the metallic 80 member 17 with the match board, and serve to prevent disconnection at this point. Thus by these metal strips, together with the members 17, and the dovetailing arrangement of the edges of the match board with 85 said members a firm and strong binding is provided for the match board to prevent a splinting, warping, or twisting of the same.

As shown in Fig. 7, portions 28 of the match board extend beyond the cope and drag sections, and such projecting portions are reinforced by metal rods 29. If desired, a suitable bracket 30 can be attached to such projecting ends to which a vibrator may be attached, if desired. The handle in addition 95 to serving the functions of the lever as hereinafter described, also serves the usual function of hand clasps.

Structural changes are, of course, contemplated provided they are maintained within 100 the scope of the appended claims.

I claim:

1. In a molder's flask, the combination of a match board, a cope section, a drag section, members arranged upon opposite sides of the match board, centering members carried by the cope section, centering members carried by the drag section, said centering members being adapted to engage the members carried by the match board whereby the cope and drag sections are each independently centered with respect to the match board, substantially as described.

2. In a molder's flask, the combination of a match board, a cope section, a drag section, vertically extending oppositely disposed members on the match board, centering members on the cope section arranged to engage said vertical members, centering members on the drag section arranged to engage said vertical members whereby the cope section and drag section are independently centered with respect to the match board, substantially as described.

3. In a molder's flask, the combination of a match board, a cope section, a drag section, members arranged upon opposite sides of the match board, centering members carried by the cope section, centering members carried by the drag section, said members be-

- ing adapted to engage the members carried by the match board whereby the cope and drag sections are independently centered with respect to the match board and the centering members carried by one of said drag sections telescoping with respect to the centering members carried by the other of said sections when the sections are placed in position, substantially as described.
- 10 4. In a molder's flask, the combination of a match board, a cope section, a drag section, vertically extending oppositely disposed members on the match board, centering members on the cope section arranged to engage with said vertically extending members, centering members on the drag section arranged to engage with said vertically extending members whereby the cope section and drag section are independently centered with respect to the match board, and the centering members on one of said sections telescoping with the centering members on the other of said sections when the sections are placed in position, substantially as described.
- 15 5. In a molder's flask, the combination of a match board, a cope section and a drag section, lever members on the cope section, lever members on the drag section, said lever members acting to initially lift said sections away from the match board, and means for independently centering the cope and drag sections with respect to the match board, substantially as described.
- 20 6. In a molder's flask, the combination of a match board, a cope section, a drag section, handles on the cope section, handles on the drag section, said handles being arranged to form levers to effect an initial lifting of the cope section and drag section away from the match board, and means for independently centering the cope and drag sections with respect to the match board, substantially as described.
- 25 7. In a molder's flask, the combination of a match board, a cope section, a drag section, members arranged upon an opposite side of the match board, centering members carried by the cope section, centering members carried by the drag section, said centering members being arranged to engage the match board members whereby the cope and drag sections are each independently centered with respect to the match board, a lever carried by the cope section, a lever carried by the drag section, said lever acting to

initially lift such sections away from the match board, substantially as described.

8. In a molder's flask, the combination of a match board, a cope section, a drag section, metal strips disposed along opposite sides of the drag board and in alinement with corresponding edges of the cope and drag sections, lever members on the cope section, lever members on the drag section, said members acting to initially lift the sections from engagement with the match board and said levers being arranged to have one end thereof bear against said strips, substantially as described.

9. In a molder's flask, the combination of a match board, a cope section, a drag section, metal strips disposed along opposite sides of the match board and in alinement with corresponding edges of the cope and drag sections, lever members on the cope section, lever members on the drag section, said members serving to initially lift the sections away from the match board, said lever members being arranged to have their acting ends bear against said strips, and means for independently centering the cope and drag section with respect to the match board, substantially as described.

10. In a molder's flask, the combination of a match board, a cope section, a drag section, metallic members arranged along opposing edges of said match board, said members being cut away to permit a dovetailing of the edges of the match board with the members and metal strips along the point of juncture of the match board and metallic members, substantially as described.

11. In a molder's flask, the combination of a match board, a cope section and a drag section, metallic members along opposing edges of said match board, said members being cut away to permit a dovetailing of the edges of the match board therewith, a vertically extending member from each of said metallic members, centering members on the cope section, centering members on the drag section, each arranged to engage with the vertically extending members whereby the cope and drag sections are centered with respect to the match board and independently of each other, substantially as described.

WILLIAM SEIDEL.
